W. P. Chadwick,

Oil Press.

No. 9382.

Patented Nov. 9, 1852.

UNITED STATES PATENT OFFICE.

WILLIAM P. CHADWICK, OF EDGARTOWN, MASSACHUSETTS.

IMPROVEMENT IN OIL-PRESSES.

Specification forming part of Letters Patent No. 9,382, dated November 9, 1852.

To all whom it may concern:

Be it known that I, WILLIAM P. CHADWICK, of Edgartown, in the county of Dukes and State of Massachusetts, have invented an improvement in presses to be used on ship-board for the extraction of oil from scraps or pieces of whale-blubber; and I do hereby declare that the same is fully described and represented in the following specification and the accompanying drawings, letters, figures, and references thereof.

Of the said drawings, Figure 1 denotes a side view; Fig. 2, a vertical, central, and longitudinal section; Fig. 3, a vertical and transverse section; and Fig. 4 is a horizontal and longitudinal section of my improved press.

In the said drawings, A represents a metallic box or vessel, made with a cover or lid, B, which is made to turn up or down on hinges *a a*, &c., and is provided with clasps *b b* or other suitable contrivances for the purpose of confining it down while the pressure is being given to the contents of the box. The sides of the box are perforated with numerous holes, as seen at *c c*, &c.

Through the middle of and within the box I arrange a long screw, B', which I so apply to the head or end *d* of the box that it can not only be revolved on its axis, but be stationary so far as an endwise movement of it is concerned—that is to say, such screw is provided with a ring-projection, *e*, which is placed between the external surface of the end *d* and the internal surface of a cap or collar, *f*, that encircles the screw and is fastened to the end of the box. The screw works through a screw-nut, C, to which a movable platen, D, is fixed, the said platen being similar in shape to the end of the box, and made to move on guides or rods *h h h*, arranged as seen in the drawings. The screw is provided with a crank, E, or other suitable means of enabling a person to turn it or cause it to revolve. When put in revolution in the right direction it will cause the platen to move or be drawn toward the end *d*, and if in the space between the said end and the platen scraps of whale-blubber be placed, they will be compressed so as to expel the oil that may be in them, which oil will run through the holes *c c c*, &c., and out of the press.

By arranging the screw within the body of the box and to work through the platen, so as to draw it toward the end *d* of the box, the

blubber in the box, when the press is in use, serves to keep the screw well oiled and prevents it from getting rusted. Besides this, the press is reduced to about half the length it would be were the screw to be arranged on the outside of the platen, as it is in other presses. Another advantage results from placing the screw within the box, in the protection it thus receives from the box, especially against the action of sea-water.

As this press is designed to be used on board of whale-ships, it will readily be seen that from the uncertain character of the whaling business it must often remain unused or out of use for considerable periods of time. Under such circumstances it is desirable to protect its working parts from rust as much as possible, which rust is sure to ensue if the sea or salt water is allowed to get on its metallic parts.

It is very essential to the easy working of the screw that it be kept well oiled, and if it is suffered to wallow in the blubber this must always be the case, and it is thus rendered a self-oiling machine, thereby obviating the necessity of a person attending to the same in the usual way, as well as effecting a saving of labor incident to such.

If the screw is placed on the outside of the press and operates by pressure against the outer end of the platen, not only will a strong frame be necessary to connect the screw-nut with the head *d*, but the whole machine would of necessity take up about double the room in length that it does under my improved form.

What I claim, therefore, as my invention is—

The arrangement of the screw within the body or interior of the box in combination with so applying it to one head of the box and to the platen that by its revolution in one direction the platen will be drawn toward the said end of the box, all substantially in manner and for the purpose as above specified, not meaning to claim the combination of a screw-platen and box, but intending to limit my claim as above described.

In testimony whereof I have hereto set my signature this 1st day of July, A. D. 1852.

WM. P. CHADWICK.
